UNITED STATES PATENT OFFICE.

HARRY T. ANDERSON, OF BUTLER, PENNSYLVANIA, ASSIGNOR TO HARRY VISSERING & COMPANY, OF CHICAGO, ILLINOIS, A CORPORATION OF ILLINOIS.

MANUFACTURE OF RAILWAY DRAFT-GEAR YOKES.

1,417,480.

Specification of Letters Patent. Patented May 30, 1922.

Application filed June 18, 1919. Serial No. 305,034.

To all whom it may concern:

Be it known that I, HARRY T. ANDERSON, a citizen of the United States, and a resident of Butler, in the county of Butler and State of Pennsylvania, have invented certain new and useful Improvements in the Manufacture of Railway Draft-Gear Yokes (Case B), of which the following is a full, clear, and exact description.

10 The invention relates to the manufacture of railway draft-gear yokes and its object is to provide an improved method of making a yoke which is made up of two forged pieces.

15 The invention consists in the several novel features hereinafter set forth and more particularly defined by claims at the conclusion hereof.

In the drawings: Fig. 1 is a side elevation 20 and Fig. 2 an end view of a blank of plate material used in forming a yoke-member. Fig. 3 is a side elevation and Fig. 4 a plan of the blank after it has been trimmed and a slot has been punched therein. Fig. 5 is a

25 side elevation and Fig. 6 a plan of the blank after the front end portion has been upset to form a reinforcement for the key-slot. Fig. 7 is a longitudinal section and Fig. 8 a plan of the blank after a flange has 30 been forged around the top, bottom and back. Fig. 9 is a side elevation and Fig. 10 a section of the blank after an opening has been cut therein to receive the draft-gear. Fig. 11 is a side elevation and Fig.

35 12 is a plan of the finished yoke. Fig. 13 is a section taken on line 13—13 of Fig. 11 and Fig. 14 is a section taken on line 14—14 of Fig. 11. Fig. 15 is a side elevation and Fig. 16 is a horizontal section showing a 40 draft-gear yoke which is adapted for tandem draft-gear and made in accordance with the invention. Fig. 17 is a section taken on line 17—17 of Fig. 15.

In the practice of the invention, a sheet 45 of flat plate steel 17 of quadrilateral form, as shown in Figs. 1 and 2, constitutes the raw blank. Next, one end of the blank is trimmed so it will be round, as shown at 18 in Fig. 3, and the front ends are cut obliquely, as at 19, and rounded as at 20, and a slot 21 is also cut through the plate. Next, the front end portion of the blank is upset or forged as at 22 to form a reinforcement for the key-slot 21 which was previously cut 55 therein so that a die member can be inserted

to back up against the surrounding metal while it is being upset. At the conclusion of this step, the blank will be in the form shown in Figs. 5 and 6. Next, the marginal portion of the blank is bent at substantially 60 a right angle to form a top flange 24, a curved back-flange 25 and a bottom flange 26, the top and bottom flanges terminating at the inclined front ends 19 and uniting with the back flange. The web forming the 65 side adjacent the front end of the blank is also bulged as at 27, so that the blank will then be of the form shown in Figs. 7 and 8. Next, an opening 28 is cut in the side or web of the blank leaving an edge 29 at the 70 front and an edge 30 at the back. This opening is of suitable size and form to receive or form a pocket for the draft-gear of usual construction. At the same time that these openings 28 are formed, the slots 75 21, as shown in Fig. 14, are elongated so they will be of sufficient size to receive the key for securing the coupler-butt to the yoke.

The foregoing practice is followed to 80 make two blanks 33 and 34 which are alike in all respects, except that the outer face of the marginal flanges on one blank are of such size that they will fit against the inner face of the marginal flange of the other 85 blank, so that the flanges, when placed together, as shown in Figs. 11 to 14, will lap one another. The two blanks are then secured together by rivets 35 which will pass through the flanges of both yoke-members. 90

In Figs. 15 to 17, there is illustrated a yoke for tandem draft-gears which is manufactured according to the method hereinbefore described. The yoke blanks are formed as heretofore described, but in lieu 95 of a single opening 28, openings 28' are formed in the side portion of each member and a central column 40 is left between the openings and in the web or side of the blank. Sometime before the yoke-members are riveted together, the central portions of the columns 40 and the web portion 41 in back of the rear slot 28' are bulged so that when they are assembled their inner faces will fit together and abut and holes are punched in 100 these abutting portions and rivets 42 secure the central portions of the yoke blanks together. 105

The invention exemplifies a simple method for producing a yoke which is made up of 110

two forged pieces having lapped flanges extending around the top, bottom and back of the yoke.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. That improvement in the manufacture of yokes for railway draft gear which consists in forging top and bottom flanges on a plate metal blank, forging on a second blank similar flanges which are adapted to overlap the flanges on the first blank when the blanks are placed side-by-side, forming a draft-gear pocket in the webs between the front and rear ends, and securing the plates together in spaced relation with the flanges thereof in overlapped relation.
2. That improvement in the manufacture of yokes for railway draft gear which consists in forging top, bottom and back flanges on a plate metal blank, forging on a second blank similar flanges which will overlap and be within the flanges on the first blank when the blanks are placed side-by-side, forming a draft-gear pocket in the webs between the front and rear ends and the top and bottom flanges and securing the plates together in spaced relation with the flanges thereof in overlapped relation.
3. That improvement in the manufacture

of yokes for railway draft-gear which consists in forging marginal flanges on the top and bottom of a pair of plate-metal blanks and forming the flanges on one plate so they will overlap and fit within the flanges on the other blank, forming a draft-gear pocket in the intermediate portion of the webs of the blanks, and securing the plates together side - by - side in spaced relation with the flanges thereof in overlapped relation.

40

45

4. That improvement in the manufacture of yokes for railway draft-gear which consists in forging a substantially continuous marginal flange around the top, bottom and back of each of a pair of plate-metal blanks and forming the flange on one plate so it will overlap and fit within the flange on the other blank, forming a draft-gear pocket in the intermediate portion of the webs of the blanks, and securing the plates together side-by-side in spaced relation with the flanges thereof in overlapped relation.

50

55

5. That improvement in the manufacture of yokes for railway draft gear which consists in forging marginal top and bottom flanges on a pair of plate-metal blanks, forming the flanges to overlap and so as to extend to the one end to form the top and bottom of a coupler pocket when the blanks are placed side by side, forming a draft-gear pocket in the intermediate portions of the webs of the blanks, and securing the plates together side-by-side in spaced relation with the flanges thereof in overlapped relation.
